UNITED STATES PATENT OFFICE

ENOCH ASP, OF MANISTIQUE, MICHIGAN

WIRE SUPPORT FOR INSULATORS

Application filed February 24, 1930. Serial No. 430,580.

This invention relates to an improved wire support for insulators, particularly those glass insulators of what is known as the skirt-type used on telephone poles or the like.

One of the important objects of this invention is to provide means in conjunction with such an insulator whereby the telephone wire can be conveniently and readily mounted thereon, and attached thereto without in any way twisting the telephone wire while at the same time assuring of a positive and permanent connection, which, however, can be readily released if desired or necessary.

Another important object of this invention is the provision of a wire mounting and support for insulators which itself is made of wire bent or twisted into shape, thereby rendering the same quite cheap and economical of manufacture, and which is also of such a construction that it can be readily applied to the insulator either when the same is in position on a telephone pole or by the lineman before mounting the pole.

Other and further important objects of the invention will be apparent from the disclosures in the accompanying drawings and following specification.

The invention, in a preferred form, is shown in the drawings and hereinafter more fully described.

In the drawings:

Figure 1 is a front elevation of the improved wire mounting for insulators of this invention showing the same supporting a wire on an insulator.

Figure 2 is a top plan view of the same.

Figure 3 is a side elevation of the apparatus.

Figure 4 is a detail view of one of the wire gripping elements.

As shown in the drawings:

The reference numeral 10 indicates generally the glass insulator to which the wire mounting of this invention is applied.

The mounting consists generally of a pair of wires 12 and 14 bent into approximately semi-circular shape, and having outwardly extending ends 16 and 18, each end being bent up in the form of a hook as best shown at 20.

The inner end of each of the wires 12 and

14 is bent into the form of a loop, and pivotally mounted in the loop end of the wire 14 is the looped end of another wire 22 which is passed through the looped end of the wire 12 at a point adjacent its looped contact with the end of the wire 14. This wire 22 is then brought forwardly in approximately a parallel relation to the wire 14, having its end terminating in a slight hook shape as shown at 24, which is adapted to be passed under a latch or the like 26 formed of a small length of wire and looped around the wire 14 at the point where the extending arm 18 branches off.

Adjoining the forward ends 16 and 18 of the wires 12 and 14 respectively is a cross-piece 28 also formed of wire and having its middle portion bent into a double loop as best illustrated at 30 in Figure 4. It will be noted that this loop is bifurcated and is adapted to receive in its crotch the telephone or electric light wire 40. The hooked ends 20 of the wires 12 and 14 are also adapted to grasp the wire 40 as shown, this positioning being accomplished when the wire 22 is thrown rearwardly, thereby leaving the wires 12, 14, and 28 in a rather loose relation in the annular groove 42 of the insulator 10. Then, when the wire 22 is bent forwardly and its end 24 fastened under the latch 26, a tightening or wedging action takes place, the hooks 20 being drawn rearwardly whereby the wire 40 is pressed closer into the notch in the bifurcated portion 30 of the wire 28, thereby providing a positioning of the wire 40, which is positive and not at all liable to work loose.

However, the same may obviously be readily released by an upward movement of the latch member 26 and a subsequent rearward movement of the clamping wire 22.

It will be seen that herein is provided a wire support for insulators which being composed of wire is quite readily available for such use and can be made up in large quantities out of scrap pieces of wire at a consequent minimum cost. Further, the same can be readily applied without the complicated twisting attachments heretofore considered necessary in securely mounting wire on such an insulator, and most of the work can be done on the ground, there-

by eliminating considerable difficulty and danger. Again, the device can be readily released, if desired, and after being so released can be used again.

- 5 I am aware that many changes may be made and numerous details of construction varied throughout a wide range without departing from the principles of this invention, and I therefore do not purpose limiting the patent
10 granted hereon otherwise than as necessitated by the prior art.

I claim as my invention:

1. A wire support for insulators, comprising elements adapted to surround an insulator, and grip a wire to be supported, said elements comprising a pair of semi-circular arms, a cross-brace connecting the forward ends of the arms, and means for locking the arms and the brace in wire-supporting position, said means comprising a wire pivotally connecting the rear ends of the arms, and adapted to draw the same and the brace into tightened wire-locking position about the insulator, and latch means for locking the wires
25 in such position, said latch means positioned on one of the arms adjacent its point of connection with the brace.

2. A wire support for insulators, comprising elements adapted to surround an insulator, and grip a wire to be supported, said elements comprising a pair of semi-circular arms, a cross-brace connecting the forward ends of the arms, means for locking the arms and the brace in wire-supporting position, said means comprising a third arm pivotally connecting the rear ends of the two first-named arms and adapted to draw the same into tightened relation with the insulator, and a bifurcated wire-receiving crotch formed in
35 the medial portion of said brace.

3. A wire support for insulators, comprising elements adapted to surround an insulator, and grip a wire to be supported, said elements comprising a pair of semi-circular arms, a cross-brace connecting the forward ends of the arms, means for locking the arms and the brace in wire-supporting position, said means comprising a third arm pivotally connecting the rear ends of the two first-named arms and adapted to draw the same into tightened relation with the insulator, and a bifurcated wire-receiving crotch formed in
45 the medial portion of said brace, wire-gripping hooks on the forward ends of the arms,
50 and latch means to retain the end of said third arm in wire gripping and locking position.

In testimony whereof I affix my signature.
ENOCH ASP.
